necticut

Application December 13, 1954, Serial No. 33,503

Term of patent 14 years

(Cl. D26—14)

FIG. 1

FIG. 2

FIG. 3

FIG. 4

Fig. 1 is a front perspective view of a sound translating machine showing my new design;

Fig. 2 is a top plan view;

Fig. 3 is a side elevational view taken from the left of Fig. 1; and

Fig. 4 is a side elevational view showing the opposite side thereof.

The dominant features of my design reside in the panel and grille work on the front and side walls of the machine.

I claim:

The ornamental design for a sound translating machine, as shown and described.
